FUEL INJECTION MEANS FOR USE IN SUPPLYING LIQUID FUEL TO THE COMBUSTION CHAMBER OF A TURBINE

Marc Xavier Marie Sciard, Paris, France

Application February 20, 1956, Serial No. 566,687

Claims priority, application France March 16, 1955

2 Claims. (Cl. 261—90)

My invention relates to a new article of manufacture consisting of fuel injecting means employing centrifugal force and designed to be used in connection with reaction turbines.

It is well known that in conventional reaction and impulse type turbines an injector, which is ordinarily actuated by a piston-type feed pump, is used to mix the air which has been compressed in the compressor with the fuel in order to form the mixture which will be burned in the combustion chamber before its expansion in the turbine.

The feeding of a combustible fluid in this manner involves certain difficulties:

The fuel circuit is a high pressure circuit since it is necessary to inject and atomize the fuel in the air which has been compressed by the compressor.

This circuit must therefore be rendered air tight, which is not easy.

The feed pump comprises reciprocating elements which must operate under pressure and must also be air tight.

My invention seeks to overcome these difficulties by providing for injection by means of a centrifugal compressor supplied with fuel by means of a greatly simplified low pressure circuit comprising a pump and which does not comprise any reciprocating element. It is relatively easy to render the low pressure supply circuit air tight and the low pressure injection means feeding the centrifugal compressor may be readily controlled by regulating the speed of a low pressure volumetric pump. The turbulence and mixing of the fuel into the air are brought about through the juncture of a primary stream produced by the centrifugal compressor type injector which consists of a rich carbureted fuel mixture and a second stream produced by the axial or centrifugal compressor of the reaction or impulse type turbine which consists of compressed air.

According to my invention, centrifugal injection means mounted within a housing comprises a centrifugal compressor having a rotor or impeller provided with a plurality of vanes, the ends of which are curved in the direction of rotation of the rotor and the free edges of which are ribbed. The vanes are thickened at the bases by means of which they are fixed to the hub of the wheel and oblique grooves are provided in this zone near the base in such a manner as to direct the fuel atomized by a volumetric pump toward the outer portion of the vane.

Certain means for carrying out my invention will now be described purely by way of example without in any way limiting the scope of my invention to the particular embodiments which are described and shown on the accompanying schematic drawings in which:

Figure 1 is a transverse cross-section taken along the line I—I of Figure 2, showing injection means according to my invention;

Figure 2 is an axial cross-section taken along the line II—II of Figure 1, showing the same apparatus;

Figure 3 is a plan view on a larger scale showing a vane of the rotor of Figures 1 and 2;

2

Figure 4 is a section taken along the line IV—IV of Figure 3;

Figure 5 is a section taken along the line V—V of Figure 3;

5 Figure 6 is a section taken along the line VI—VI of Figure 3;

Figure 7 is a section taken along the line VII—VII of Figure 3;

Figure 8 is a detail view showing the end of a slightly modified rotor vane on a larger scale;

10 Figure 9 is a section along the line IX—IX of Figure 8; and

Figure 10 is a section taken along the line X—X of Figure 8.

15 The injection means, according to my invention, comprises, as shown in Figures 1 and 2, a casing 1 carrying a deflector 2, a rotor or impeller 3 for the centrifugal compressor which carries vanes 4, and low pressure injection means 5 controlled by a volumetric pump (not shown).

20 Each vane 4 has a specific shape (see Figs. 4—7):

Its end 6 is bent in the direction of rotation of rotor 3, as indicated by arrow F (Fig. 1).

Its free edge carries a flange 7.

25 Its foot 8 is thickened and oblique grooves 9 extending both axially and outwardly of each vane are cut into its base.

Its substantially central portion 10 is roughened near the base 8. The roughened area 11 may be seen on Fig. 7.

30 The injection means operates as follows:

The liquid fuel supplied under low pressure by a volumetric pump is thrown out by the ends of the injection tubes or low pressure atomizers 5 so as to bring about a crude atomization.

35 The small drops of liquid are drawn into the stream of air arriving at 12 (following the arrow f) which is drawn in by the centrifugal rotor 3. The finely divided fuel partially evaporates in the air. The remaining droplets are spread over the vanes 4 and guided by the grooves 9 to the roughened zone 10, where they are diverted from their axial direction and turned centrifugally outward following the line of the arrow f'.

The flange 7 is designed to provide guide means for those droplets in zone 8 which have not entered any groove 9 and maintain a layer of liquid having a certain thickness on the rectilinear portion 13 of the vanes.

40 The fuel is finally ejected at high speed in the direction of the arrow f' towards the ends 6 of the vanes; the curvature of the ends 6 of the vanes directs the stream of liquid fuel which travels at high speed in the direction of the arrow f'' against the stream of air moving in the direction shown by the arrow F' at a substantial angle of incidence.

45 The fuel which comes in under low pressure from the tubes 5 which serve as low pressure atomizers is thus very finely divided.

The ejection speed of the fuel, which must theoretically equal the product of the angular speed of rotation of the compressor (expressed in radians per second) and the radius of the rotor, is in practice about half of this value. It is thus easy to obtain an ejection speed of 200 meters per second with a vaned rotor having a diameter of some 60 centimeters and a speed of 250 revolutions per second.

50 60 In order to obtain as large an ejection speed as possible the portions 13 and 6 near the outer ends of the vanes should be highly polished.

65 Since it is necessary to provide when starting under certain circumstances an ejection of fuel at a relatively slight angle of incidence with respect to the air (a small angle between f'' and F' as seen on Fig. 4) and with a direct penetration into the secondary stream of air which

follows the direction indicated by the arrow F, the ends 6 of the vanes may be modified as shown in Figures 8, 9 and 10, on which the same reference numerals have been used as in Figures 1 to 7.

The end 6 of each vane 4 is split along the line 14, the free part 15 of the end 6 remaining straight instead of being curved, like the remainder 16 of the end 6, in the direction of rotation (show by the arrow F).

As a result of this arrangement, at very low speeds of rotation (or during starting) the thin layer of fluid is concentrated on the portion 15 of the end 6 of the vane 4 and leaves it along the line indicated by the arrow f'' at a negligible angle to the air stream following the line indicated by the arrow F'. Only a small portion of the fuel flows over the curved part 16 of the end 6 and leaves in the direction of the arrow f''' at a substantial angle to the air which flows in the direction indicated by the arrow F'.

It will, of course, be appreciated that the specific embodiments herein described may be modified by replacing various parts by equivalent elements without departing from the spirit of my invention. The grooves 9, for example, may be extended to the ejection zone, and their extended portions may be covered over.

I claim:

1. Fuel injection means for use in supplying fuel to the combustion chamber of a turbine, consisting of a centrifugal compressor comprising a housing, a rotor in said housing having a hub carrying a plurality of radially projecting vanes, means for leading a stream of air to

20

25

30

said vanes and means for projecting liquid fuel onto the bases of said vanes, each of said vanes being thicker near its base than near its outer end and having a portion of its surface lying intermediate its ends and just outwardly of said thickened portion roughened, each vane being provided with a plurality of grooves in the surface of said thicker portion for receiving said liquid fuel and guiding it toward said roughened portion, the outer ends of said vanes being curved to direct at least a portion of said fuel into said air stream at an angle to its path of travel, and deflecting means encircling said rotor for directing said fuel toward said combustion chamber after it has been flung off said rotor vanes.

2. Apparatus as claimed in claim 1 in which each vane is attached to said rotor along one of its longitudinal edges and the free longitudinal edge is provided with a lateral flange.
